UNITED STATES PATENT OFFICE.

MARTINUS ZEEN, OF GRAND RAPIDS, MICHIGAN, ASSIGNOR OF ONE-HALF TO JOHN ZEEN, OF GRAND RAPIDS, MICHIGAN.

DEVICE FOR RAISING AND LOWERING WATER-CLOSET SEATS AND LIDS.

1,276,472.

Specification of Letters Patent. Patented Aug. 20, 1918.

Application filed February 13, 1918. Serial No. 216,981.

To all whom it may concern:

Be it known that I, MARTINUS ZEEN, a subject of the Queen of the Netherlands, residing at Grand Rapids, in the county of Kent 5 and State of Michigan, have invented new and useful Improvements in Devices for Raising and Lowering Water-Closet Seats and Lids, of which the following is a specification.

10 The present invention relates to devices for raising and lowering water closet seats and lids; and its object is to provide an improved device of that character whereby such seats and lids may be raised and lowered without applying the hands thereto.

This object is attained by, and the invention finds preferable embodiment in, the structure hereinafter described and illustrated by the accompanying drawings, in 20 which:—

Figure 1 is a view in perspective of a water closet to which my invention is applied and showing the seat and lid in lowered position;

25 Fig. 2 is a side view of parts of the same, but showing the lid in raised position; and

Fig. 3 is a central vertical sectional view of the rock shafts whereon the seat and lid are carried, with connected parts.

30 In the embodiment of the invention chosen for illustration by the drawings and for detailed description in the body of this specification, the water closet 1 is provided with the seat 2 and lid 3, they being swingable members mounted in the following manner: The upper member—the lid 3—has a hollow rock shaft 4, journaled at 5, and the arm portions 6 turning with said shaft, and has also a continuous elongated deflected slide- 35 way 7, preferably in form the arc of a circle as shown, such slideway being a slot cut through the plate 8, fixed on said shaft. These parts, the lid 3, shaft 4, arm portions 6 and plate 8 form a unitary swingable member provided with the slideway 7.

The lower member—the seat 2—has a shaft 9, rockable in the hollow shaft 4, arm portions 10 turning with said shaft 9, and a continuous elongated deflected slideway 11, 40 preferably in form the arc of a circle as shown, such slideway being a slot cut through the plate 12, fixed on said shaft 9. These parts, the seat 2, shaft 9, arm portions 10 and plate 12 form a unitary swingable member provided with the slideway 11.

The lid and seat, being thus similar in construction and mounting, are also similarly raised and lowered, and in the following manner:

Movable elements, as the rod 13 for raising and lowering the seat and the rod 14 for raising and lowering the lid, are swingably mounted at their lower ends 15, 16, as to the operating foot levers 17, 18, respectively. The upper ends of said elements are provided with portions, as the transverse bolts 19, 20, which are slidable in the slideways 11, 7 respectively.

When the parts are in the position shown in Fig. 1, the lid may be lifted by pressing 70 the foot on the pedal portion 21 of the lever 18, thus raising the rod 14 and thereby the lid through the engagement of the upper portion 20 of the rod with the upper side of the slot or slideway 7. When the lid is thus 75 raised to the position shown in Fig. 2 and the foot pressure is released, the rod's upper end portion 20 travels by gravity along the slideway to its opposite end (which is now the lower end) and occupies the position 80 shown at the right hand side of Fig. 2. By pressing the pedal portion 22 of the other lever 17, the seat may be raised in like manner. When the lid or seat is to be lowered, the pedal portion of the lever, (which is now 85 in the same position as before the lid or seat was raised) is pressed by the foot, thus causing the upper end portion of the rod to engage the upper side of the slot or slideway, (as shown at the right hand side of Fig. 2), 90 and as the seat or lid is lowered (the foot pressure being released), the rod's upper end travels by gravity along the slideway to its opposite end and occupies the position shown in Fig. 1.

95 The levers are so juxtaposed, as shown, that either may be operated or both together by a single pressing of the foot.

It will be seen that the nuts and heads of the bolts 19, 20 slidably confine the elements 100 13, 14 in the closed slot slideways.

Counterweights 23, 24 are desirably provided for the several shafts, as shown.

The invention being intended to be particularly pointed out by the claims, is not 105 to be limited to or by details of construction shown or described.

I claim:

1. In a device of the character described, a swingable member having a continuous de- 110

2
flected slideway; a movable element having one end swingably mounted and having its other end slideable in the slideway to one position wherein said element is adapted to be moved to swing said member in one direction and to another position wherein said element is adapted to be moved to swing said member in the opposite direction.

- 5 2. In a device of the character described; a swingable member having a continuous deflected slideway; a lever; an element pivotally connected at one end to the lever and having its other end slideable in the slideway to one position wherein said element is 10 adapted to be moved by the lever to swing said member in one direction and to another position wherein said element is adapted to be moved by the lever to swing said member in the opposite direction.
- 15 3. In a device of the character described; a swingable member having in fixed relation thereto a hollow rock shaft and a continuous deflected slideway; a second swingable member having in fixed relation thereto a shaft 20 rockable in the hollow shaft and a second continuous deflected slideway; a pair of le-

vers juxtaposed for operation severally or together; a pair of elements pivotally connected at one end to the levers respectively and having their other ends slideable in the 25 slideways respectively to one position wherein said elements are adapted to swing said members respectively in one direction and to another position wherein said elements are adapted to swing said members respectively in the opposite direction.

4. In a device of the character described; a swingable member having an elongated slideway; a movable element having one end swingably mounted and having its other end 30 slideably confined in the slideway and slideable therein to one position wherein said element is adapted to be moved to swing said member in one direction and to another position wherein said element is adapted to be 35 moved to swing said member in the opposite direction.

In testimony whereof I have hereunto set my hand at Grand Rapids, Michigan, this 9th day of February 1918.

MARTINUS ZEEN.
